DESIGN FOR A PORTABLE BUILDING

Arthur E. Waterman, Fort Atkinson, Wis., assignor to James Manufacturing Company, Fort Atkinson, Wis., a company of Wisconsin

Application October 8, 1942, Serial No. 108,465

Term of patent 14 years

To all whom it may concern:

Be it known that I, Arthur E. Waterman, a citizen of the United States, residing at Fort Atkinson, in the county of Jefferson and State of Wisconsin, have invented a new, original, and ornamental Design for a Portable Building, of which the following is a specification, reference being had to the accompanying drawing, forming part thereof.

I claim:

The ornamental design for a portable building, as shown.

ARTHUR E. WATERMAN.
